UNITED STATES PATENT OFFICE

JOHN FREDERICK PALMER, OF MILWAUKEE, WISCONSIN, ASSIGNOR TO PALMER PRODUCTS, INC., OF WAUKESHA, WISCONSIN, A CORPORATION OF WISCONSIN

DISPENSER

Application filed June 11, 1928. Serial No. 284,430.

This invention relates to dispensers.

The dispenser to which the invention applies in particular has a receptacle to contain the material to be dispensed and a valve to control the flow of the material.

An object of the invention is to provide a dispenser from which the receptacle cannot be removed without breaking the same.

Another object is to provide an improved joint between the receptacle and the dispensing valve.

Another object is to provide a dispenser which is efficient, sturdy and economical to manufacture.

According to one phase of the invention, the receptacle is held against removal from the dispensing valve by a latch which is inaccessible until the receptacle is broken.

According to another phase of the invention, the dispensing valve carries a socket and a threaded nipple, the base of the receptacle is arranged in the socket and connected by a ferrule to the nipple, and a gasket is arranged between the nipple and the valve to prevent leakage therebetween of the material to be dispensed.

Dispensers embodying the invention are illustrated in the accompanying drawings in which the views are as follows:

Fig. 1 is a central vertical longitudinal section through a dispenser.

Fig. 2 is a horizontal section on the line 2-2 of Fig. 1.

Fig. 3 is a central vertical section showing a modified form.

Fig. 4 is a horizontal section on the line 4-4 of Fig. 3.

Fig. 5 is a central vertical section showing another modified form.

Fig. 6 is a horizontal section on the line 6-6 of Fig. 5.

Figs. 7 and 8 are central vertical sections showing other modified forms.

Figs. 1 and 2

The dispensing valve has a cylinder 1 with a head 2 threaded in the rear end thereof and a plunger 3 operable through the forward end thereof.

The head is threaded into a bracket 4 which may be fastened to a suitable support.

The plunger has a lateral recess 5 to connect the cylinder with the outlet port 6 when the plunger is moved inwardly.

The inner end of the plunger is provided with a valve 7 to engage a seat 8 arranged in the forward end of the cylinder to preclude the escape of liquid.

The inlet port 9 in the cylinder head is controlled by a valve 10 on a rod 11 carried by the plunger.

The rod is slidale into the plunger and has a head 12 to limit its outward movement from the plunger.

The spring 13 is arranged in the plunger to bias the rod outwardly therefrom.

A spring 14 arranged in the cylinder biases the plunger outwardly to normal position.

Liquid is supplied to the valve from the receptacle 15 arranged in a socket 16 on the valve.

A threaded nipple 17 is arranged in the socket and a passage 18 extends from the nipple through the cylinder casing and communicates with the inlet port 9 in the cylinder head.

The receptacle may be made of glass or other suitable substance and has a ferrule 19 which provides a nut 20 to screw onto the nipple and thereby hold the receptacle in the socket.

A gasket 21 is arranged in the bottom of the socket and is compressed by the nut 20 to prevent leakage of the liquid.

A pawl 22 is arranged on the ferrule to engage ratchet notches 23 in the socket walls to prevent the ferrule and nut from being unscrewed from the nipple.

The coupling thus provided locks the receptacle to the valve and prevents the gasket from being released of pressure.

The receptacle may be filled by removing the plug 24 at the top thereof.

When the receptacle becomes broken and has to be replaced by a new one, it may be removed by chipping away the glass near the pawl and then releasing the pawl and unscrewing the receptacle from the socket.

Figs. 3 and 4

The coupling here shown is locked by a pawl 25 arranged in the socket wall and engaging ratchet notches 26 in the ferrule of the 5 receptacle.

Figs. 5 and 6

The coupling here shown has a ferrule 27 threaded to the socket walls and the base of the ferrule struck up to form ratchet notches 28 near the outer periphery.

A pawl 29 is arranged on the bottom of the socket to engage the notches in the base of the ferrule.

15 A central opening 30 in the base of the ferrule communicates with the passage 18 in the cylinder casing.

A gasket 31 is arranged around the opening 30 between the base of the ferrule and 20 the bottom of the socket to provide a tight joint therebetween.

Fig. 7

The ferrule base is held in the socket by a 25 lock nut 32 arranged on the nipple.

The nut may be prevented from being loosened by a set screw 33 arranged in the socket wall and bearing against the ferrule to prevent its turning.

30 A gasket 34 is compressed in the bottom of the socket.

Fig. 8

The coupling here shown is provided with 35 a bayonet joint having a cam groove or thread 35 arranged in the socket wall and lugs 36 on the ferrule to fit in the thread.

A set screw 37 may be provided in the socket wall to hold the ferrule from loosening.

40 A gasket 38 in the bottom of the socket is compressed by the ferrule.

Of course, the individual liquid dispensing faucet may assume various forms within 45 the spirit of the invention as hereinafter defined in the claims.

The invention is hereby claimed as follows:

1. A dispensing faucet having in combination therewith a glass receptacle for the 50 liquid to be dispensed thereby, a socket arranged on said faucet and having ratchet notches in the walls thereof, a threaded nipple arranged in said socket and having a passage communicating with the chamber of said faucet, a ferrule base for said receptacle having a threaded opening to screw onto said threaded nipple and draw and hold said base in said socket, a gasket arranged in said socket to be compressed by said base to provide 60 and maintain a tight connection between said receptacle and said faucet, and a pawl arranged on said base to engage said ratchet notches to prevent the base from being loosened in said socket.

65 2. A liquid dispenser comprising, in combi-

nation, a frangible receptacle for liquid, a faucet having an inlet and a discharge outlet, an externally threaded nipple arranged on said faucet in communication with said inlet and opening into said receptacle, a socket arranged on said faucet around said nipple and having notches in the side wall thereof, a ferrule carried by said receptacle and threaded on said nipple, a gasket arranged in said socket to be compressed by said ferrule and form a tight joint between said ferrule and said socket, and a pawl carried by said ferrule and engaging said notches to prevent said ferrule from being loosened in said socket.

70 3. A liquid dispenser comprising, in combination, a frangible receptacle for liquid, a faucet having an inlet and a discharge outlet, an externally threaded nipple arranged on said faucet in communication with said inlet and opening into said receptacle, a socket arranged on said faucet around said nipple and having notches in the side wall thereof, a ferrule carried by said receptacle and threaded on said nipple, a gasket arranged in said socket to be compressed by said ferrule and form a tight joint between said ferrule and said socket, and a pawl struck out from the upper edge of said ferrule and engaging said notches to prevent said ferrule from being loosened in said socket.

75 4. A dispenser, comprising a dispensing valve having means for securing the same to a support, a socket carried by said valve, a frangible receptacle having the base thereof arranged within said socket, means to secure the base of said receptacle in said socket, a gasket arranged in said socket to prevent leakage of the material to be dispensed, and means to prevent said receptacle from being removed from said socket without breaking the same.

80 5. A dispenser, comprising a dispensing valve having means for securing the same to a support, a socket carried by said valve, a frangible receptacle having the base thereof arranged within said socket, a ferrule fastened to said base and having means to secure the same in said socket, a gasket arranged in 85 said socket to prevent leakage of the material to be dispensed, and ratchet means to prevent removal of said receptacle from said socket arranged in said socket and inaccessible from the outside of said dispenser.

85 6. A dispenser, comprising a dispensing valve having means for securing the same to a support, a socket carried by said valve, a threaded nipple arranged within said socket and communicating with the interior of said valve, a receptacle having the base thereof arranged within said socket, a ferrule fastened to said base and having means to thread the same upon said nipple and secure said receptacle to said valve, and a gasket arranged 90

between said ferrule and said valve to prevent leakage therebetween of the material to be dispensed.

7. A dispenser, comprising a dispensing valve having means for securing the same to a support, a socket carried by said valve, a threaded nipple arranged within said socket concentric thereto and communicating with the interior of said valve, a receptacle having the base thereof arranged within said socket, a ferrule fastened to said base, a nut arranged within said base and carried by said ferrule to engage said nipple and secure said receptacle to said valve, and a gasket arranged between said ferrule and said valve to prevent leakage therebetween of the material to be dispensed.

8. A dispenser, comprising a dispensing valve having means for securing the same to a support, a socket carried by said valve, a threaded nipple arranged within said socket and communicating with the interior of said valve, a receptacle having the base thereof arranged within said socket, a ferrule fastened to said base and having means to thread the same upon said nipple and secure said receptacle to said valve, a gasket arranged between said ferrule and said valve to prevent leakage therebetween of the material to be dispensed, and means to prevent said receptacle from being rotated to remove the same from said valve.

9. A dispenser, comprising a dispensing valve having means for securing the same to a support, a socket carried by said valve, a threaded nipple arranged within said socket and communicating with the interior of said valve, a receptacle having the base thereof arranged within said socket, a ferrule fastened to said base and having means to thread the same upon said nipple and secure said receptacle to said valve, a gasket arranged between said ferrule and said valve to prevent leakage therebetween of the material to be dispensed, and means arranged entirely within said socket to prevent said receptacle from being rotated to remove the same from said valve.

10. A dispenser, comprising a dispensing valve having means for securing the same to a support, a socket carried by said valve, a threaded nipple arranged within said socket and communicating with the interior of said valve, a frangible receptacle having the base thereof arranged within said socket, a ferrule fastened to said base and having means to thread the same upon said nipple and secure said receptacle to said valve, a gasket arranged between said ferrule and said valve to prevent leakage therebetween of the material to be dispensed, and means to prevent said receptacle from being removed from said socket without breaking the same.

11. In combination with dispensing containers and the like, a cup-shaped member

having a central threaded aperture, said member designed to cover the neck portion of the container, a threaded mounting for receiving the cup-shaped member, said mounting having an annular flange for housing the cup-shaped member, a plurality of ratchet teeth formed along the inner surface of the flange, and a resilient locking finger struck from the walls of the cup-shaped member, adapted to lockingly engage the ratchet teeth of the flanged mounting to prevent the inadvertent unscrewing of the cup-shaped member.

In witness whereof, I have hereunto subscribed my name.

JOHN FREDERICK PALMER.
